SCULPTURAL ORNAMENT

Amnon Michaeli, 135-03 73rd Terrace, Queens,
Kew Gardens Hills, N.Y. 11415

Filed May 11, 1973, Ser. No. 359,489

Term of patent 14 years

Int. Cl. D26—99, 01, 05

U.S. Cl. D48—7 F

FIG. 1

FIG. 2

FIG. 4

FIG. 3

FIG. 1 is a top plan view of a sculptural ornament of my new design;

FIG. 2 is a side elevational view taken from any side thereof;

FIG. 3 is a bottom plan view thereof; and

FIG. 4 is a cross-sectional view along the line 4—4 of FIG. 1.

I claim:

The ornamental design for a sculptural ornament, as shown and described.
